UNITED STATES PATENT OFFICE.

JULIA PERLZWEIG, OF YONKERS, NEW YORK.

PROTECTOR.

Application filed November 11, 1925. Serial No. 68,279.

My present invention relates to sanitary protectors and while primarily intended for catamenial purposes, is not limited to such use.

It is among the objects of the invention to provide a device of the above type, of simple and relatively inexpensive construction, which shall be comfortable to wear and more particularly one which shall substantially preclude chafing as by folding or wrinkling of the parts held against the body, which shall effectively protect against cold, whether as a consequence of evaporation, or by the entry of drafts, and which shall avoid pressure due to the use, for instance, of metallic parts or buckles or of any other hard or stiff reinforcing, anchoring or fastening element.

Among other objects are to provide a device of the character set forth, which may be easily applied to the body and which is unlikely to slip from adjusted position even though the wearer indulges in vigorous movement, but which is yet readily accessible for replacement of the pad.

In the accompanying drawings in which are shown one or more of various possible embodiments of the several features of the invention,

Fig. 1 is a view of the garment in open or extended position,

Fig. 2 is a front view showing the garment in use,

Fig. 3 is a rear view showing the garment in use,

Fig. 4 is a transverse sectional view showing the garment in use, and;

Fig. 5 is a view similar to Fig. 1 indicating an application of the garment with a hospital pad for an alternative use.

Referring now to Fig. 1 of the drawings, I have shown a preferred embodiment of the garment, which in open position as shown, includes an apron shaped protective shield or panel 10 preferably of rubberized fabric, the lateral segment parts 11 of which are disposed with the warp and woof of the fabric in oblique or bias relation, as clearly shown. Preferably, bands of tape 12 secure the lateral segments 11 to the main panel and the entire apron shaped panel is bound by tape at 13.

The shield or panel preferably has at the reduced or rear end thereof, a non-elastic fabric extension or anchoring plaque 14 of substantial area preferably also bound with

tape as shown at 15, to the lateral edges of which are directly attached as by stitches 16 the ends of a continuous elastic belt strap 17.

As shown best in Fig. 3, the anchoring plaque 14 covers the middle of the wearer's back immediately below the belt and the protective shield upon which is to be carried the usual absorbent pad 18. The shield extends forward from said plaque between the thighs of the user and is secured in position by a pair of straps 19 anchored as shown, by a line of stitches 20 symmetrical of the forward part of the belt at the lower edge thereof, said straps being secured as by stitches 21 at spaced parts symmetrically of the forward or wider edge of the protector shield 10. As shown, the straps 19 are spaced by a greater distance at the belt end than they are at the shield end so that in use, these straps will diverge upward as best shown in Fig. 2 from the forward part of the shield to the belt. In addition, there are preferably provided, elastic thigh straps 22 connected each as shown, at one end 23 to the corresponding taped edge of the shield immediately beyond the segment part 11 and at the other at 24 to the segment part at the forward 75 taped edge thereof.

Preferably, a pair of straps 25 connect the lateral edges of the anchoring plaque 14 to the belt, said straps extending obliquely as shown in Fig. 3 so that in use, 90 the anchor plaque 14 is held flat and smooth against the back of the wearer without wrinkling and in turn, retains the rear of the shield against the body without wrinkling or binding. The oblique spaced diverging forward straps 19 draw apart the forward edge of the shield. The portion of the shield extending between the thighs is thus drawn apart both at its forward and its rear portion and held taut, yet without binding, thereby maintaining the absorbent pad 18 thereon in close contact, pressed in flat condition and without wrinkling against the body. The warp and woof of the bias cut segments extend respectively approximately, vertically and horizontally and, accordingly, when the thigh straps are closed will follow and become adapted without wrinkling to the curvature of the thigh. By the construction described, the edges of the shield are drawn securely against the body and adequate protection is thereby af-

forded against the entry of air or the evaporation of moisture and the wearer will be protected thereby from cold. In warm weather, the garment may thus serve as a 5 substitute for bloomers.

Preferably, each strap element 19 is formed in a single piece at its anchored end with the corresponding strap 25, said combined strap stitched as shown intermediate 10 its ends to the lower edge of the belt, the rear end thereof being stitched to the anchoring plaque 14 and the forward end serving for holding up the forward end of the shield or protector 10.

15 Preferably both the thigh straps 22 and the holder straps 19 by which the forward end of the shield is sustained are each formed of two segments detachably connected together at their adjacent ends by snap fasteners 26.

20 Accordingly, as shown, in the expanded view, Fig. 1, each thigh strap is composed of the two elements 22^a and 22^b stitched respectively to the lateral and forward edges 25 of the panel and the holder straps are formed of complementary pieces comprising a short oblique or tangential portion 19^b at the belt and a complementary short portion 19^a at the wider or forward edge of the shield, the pair 30 of forward straps being symmetrically spaced near the longitudinal axis of the shield.

35 I deem it preferable to lay the pad flat in position on the shield, since the pad will be held by the attachment of the shield against slipping and the binding or wrinkling is precluded that might result from separately anchoring the ends of the pad instead of merely resting it in the shield. If 40 desired, however, the pad may be removably pinned in position at its forward end.

45 Replacement of the pad is readily effected without removing the garment, by simply opening the snap fasteners of the holder straps 19 and the pad not being pinned or pinned only at its forward end, can easily be taken out, a fresh one applied and the fasteners again snapped closed.

50 The garment, as will be readily seen, may be used substantially in open position shown in Fig. 1 as a sanitary apron.

55 For hospital use, in lieu of the small pad, there would be used a pad such as shown at 27 in Fig. 5 of much larger dimensions, substantially of the size and shape of the shield.

60 It will thus be seen that there is herein described a device in which the several features of this invention are embodied, and which device in its action attains the various objects of the invention and is well

suited to meet the requirements of practical use.

As many changes could be made in the above construction, and many apparently widely different embodiments of this invention could be made without departing from the scope thereof, it is intended that all matter contained in the above description or shown in the accompanying drawings, shall be interpreted as illustrative and not in a 70 limiting sense.

Having thus described my invention, what I claim as new and desire to secure by Letters-Patent of the United States is:—

1. In a sanitary protector, in combination, 75 an elastic belt strap, a plaque of fabric secured directly at the rear part of said belt and a pair of strap members anchored at the forward part of the belt and converging downward to the forward edge of the plaque 80 and secured thereto at their lower ends in symmetrically spaced relation to retain said plaque flat between the thighs, said plaque having a pair of bias-cut lateral segments 85 for adaptation to the curvature of the thighs and elastic straps connecting said segments to the rear portion of the plaque.

2. A sanitary protector comprising a supporting elastic belt strap, a flat shield of rubberized fabric having an extension at its 90 rear end of substantial width and connected directly to said belt strap, a pair of elastic straps attached intermediate their ends directly to said belt, attached at their rear ends to the plaque extension and converging obliquely downward at their forward parts 95 from said belt and connected at their forward ends symmetrically of the forward edge of the shield to support the same.

3. A sanitary protector comprising a flat 100 shield of rubberized fabric having substantially the shape of an apron, the lateral segments of said shield being bias cut for more ready adaptation in use to the form of the thighs, said shield having a non-elastic fabric anchoring plaque of substantial width attached to the rear thereof, an elastic belt strap connected to the sides of said anchoring plaque, thigh straps connecting said lateral segments to the sides of said plaque, 110 and elastic support straps connected at their lower ends in symmetric spaced relation at the front of said shield and connected at their upper ends to the belt and converging downwardly from said belt to the shield. 115

Signed at New York in the county of New York and State of New York this 27th day of October, A. D. 1925.

JULIA PERLZWEIG.
